UNITED STATES PATENT OFFICE.

JOHN J. BURK, OF BUFFALO, NEW YORK, ASSIGNOR TO EDWARD M. JEWETT, OF SAME PLACE.

BARREL-STAVE.

SPECIFICATION forming part of Letters Patent No. 243,205, dated June 21, 1881.

Application filed March 10, 1880. (No model.)

To all whom it may concern:

Be it known that I, JOHN J. BURK, a subject of the Queen of Great Britain, residing in the city of Buffalo, in the county of Erie and State of New York, have invented certain new and useful Improvements in Staves for Barrels, of which the following is a specification.

The object of this invention is to render the form or shape of a stave permanent, and to increase the strength and durability and improve the appearance of the same, and also to lessen the cost of its construction.

Heretofore staves have been prepared in the wet or steamed state, which leaves them in a condition to shrink and warp out of shape while drying.

My invention obviates this objection; and it consists of a stave compressed between rollers while in a dry state, so as to increase its width and diminish its thickness, thereby making it more dense, and consequently increasing its strength and durability, and also improving its appearance, as will be more clearly understood by reference to the drawings, in which—

Figure 1 is a front view of a stave; Fig. 2, a side elevation, and Fig. 3 an end view. Fig. 4 represents a stave partly completed by my process, and Fig. 5 is a side elevation of the same.

The stave, after being cut or otherwise made in the ordinary way and made perfectly dry, is passed through powerful rollers of the proper form to give it the necessary transverse curve so as to compress it about one-third of its thickness. The rollers are made one with a concave face on the periphery and the other with a convex face, the curve being of the necessary form to curve a stave (transversely) for a barrel, keg, cask, or other similar article.

In Figs. 4 and 5, A represents the finished or compressed portion of a stave, and B the part which has not been acted on or compressed. It will be noticed that the finished portion is wider and thinner than the unfinished portion.

Some of the advantages resulting from this process or mode of construction are as follows: A stave constructed in this way is in a better and more permanent shape than firing

or trussing can possibly leave it, and it thereby produces a better shaped barrel. The compressing-rollers smooth the rough parts, close up the worm-holes, and bring a crooked or warped stave into proper shape, thereby making it possible to use staves that would otherwise be worthless. It leaves the timber in a more condensed condition, and consequently in better shape to resist the influence of either a dry or damp atmosphere, or to stand excessive heat, such as a barrel would have to stand when used for water-lime, slaked lime, &c. The wood being in a more condensed state, its absorbing qualities are much less, and a barrel made therefrom is more nearly air-tight. When used in a barrel it obviates the necessity of firing and retrussing, which is quite an item in the cost of manufacture, besides the saving of insurance in a large shop, where the firing of barrels is dispensed with. The barrel being cold when hooped makes a better barrel than when fired, as at least ninety per cent. of fire-made barrels are hooped while yet warm, and the timber does not cease to shrink until it becomes entirely cold. It produces a saving of at least five per cent. in timber, as it increases in width, as shown in Figs. 4 and 5, while being compressed, so that more barrels can be made from a given number of staves than by the old way. The shape of a stave formed dry in this way being permanent, it is impossible for a stave to "fall in" or bring a convex surface inside, instead of outside, of a barrel, as is often the case when fire-made. It reduces the cost of making at least twenty-five per cent. Timber prepared in this way should not be boiled or steamed, but should be prepared cold and dry.

I do not here claim the mode of preparing staves above described, as the same may form the subject of a separate application for Letters Patent; but

I claim—

As a new article of manufacture, a bent wooden stave having condensed and laterally-spread fibers, as set forth.

JOHN J. BURK.
